ADJUSTABLE FOLDING TABLE

Raymond M. Owen, New York, N. Y.

Application May 8, 1937, Serial No. 141,521

3 Claims. (Cl. 311—93)

The invention here disclosed relates to adjustable and folding tables.

Special objects of the invention are to provide a table for holding heavy books for reading purposes, which can be easily adjusted to suit the comfort and convenience of the reader and which as required, may be quickly unfolded and set up for use or folded to be put away, which in the folded state will take up but small space, which 10 will be light but strong, neat in appearance and generally suitable and desirable for various table uses.

The objects mentioned and others of a desirable nature are attained in the present invention 15 by the novel features of construction, combinations and relations of parts hereinafter described and broadly claimed.

The drawings accompanying and forming part of the specification illustrate practical embodiments of the invention, but it is to be understood that various changes and modifications in structure may be made all within the true intent and broad scope of the invention.

Fig. 1 is a perspective view illustrating the 25 table set-up ready for use and showing in broken lines how the table top may be tilted at various angles when in use as a support for reading matter, or in use as a drawing board, or the like.

Fig. 2 is an enlarged broken detail of the head 30 portion of the structure.

Fig. 3 is a broken end view looking in the direction of arrow 3 in Fig. 2.

Figs. 4 and 5 are broken cross-sectional views as on lines 4—4, 5—5 of Fig. 2.

Fig. 6 is a side elevation showing the table in the collapsed or folded condition.

Fig. 7 is a broken enlarged horizontal sectional view as on substantially the plane of line 7—7 of Fig. 6.

Fig. 8 is a generally similar view illustrating a modification.

Figs. 9 and 10 are side and end views illustrating use of the table.

As shown in Fig. 1, the device consists in general of a hollow upright standard or column 10, a vertically extensible post 11, slideable in said column, a laterally projecting head or support 12, on the post and a table top 13, carried by the last mentioned and angularly adjustable about 50 its supported axis.

The column or pedestal 10, is shown as having a generally triangular base portion 14, providing mounting for the feet 15, which are shown as secured to two of the sides of such triangular 55 formation by pivot bolts 16. These pivoted feet

are shown as having substantially rectangular extensions or projections 17, beyond the points of pivotal connection with the base, providing supports at the opposite side of the column and forming when the legs are folded, as in Fig. 6, 5 extensions of the base for holding the collapsed structure upright on a floor or other support.

Friction washers are indicated at 18, in Fig. 7, for yieldably retaining the feet elements in their upfolded position. This view shows also how 10 these members may be made of sheet metal flanged along the edges to stiffen and brace them.

Suitable stops or securing means are provided for locking the feet in the outstanding divergent supporting relation, such as the stop lugs 19, 15 on the base, overstanding the upper edges of the feet as in Fig. 1, or the spring latch pins 20, Fig. 8, on the feet positioned to enter lock seats 21, in the adjacent sides of the base. The curved arrows in Fig. 1, indicate how when the column is 20 lifted off the floor the outstanding feet may be rotated about pivot centers 16, over approximately $\frac{3}{4}$ of a turn to bring them up into generally parallel relation at opposite sides of the column as in Figs. 6 and 7. Similarly, the curved 25 arrow in Fig. 6, shows how when the stand is lifted off the floor, the feet may be rotated approximately $\frac{3}{4}$ of a turn to carry them back into the projecting relation illustrated in Fig. 1. This simple stop construction has its advantages, 30 but requires, as explained, a considerable movement of the feet. With the Fig. 8 form of construction, it is only necessary to withdraw the spring latches 20, from their seats 21, whereupon the feet 15 may be simply rotated upwardly $\frac{1}{4}$ 35 of a turn to bring them into the folded positions at the sides of the column.

To hold the sliding post 11, against turning in the column, the same may be of square or other angular cross-section tubing as indicated, operating through a guide 22, of corresponding shape at the top of the column. This guide is shown as carrying a clamp screw 23 for securing the post at different levels of adjustment.

The lateral supporting arm 12, is shown as of 45 substantially square cross-section and as having a sliding and rotative mounting in the correspondingly shaped channeled head portion 24, on the top of the post. This form of mounting is provided by slotting the arm at 25, to slide and 50 rotate over a pin or bolt 26, extending across the channel at one side of the post and by slotting the end of the arm at 27, to fit over a pin or bolt 28, crossing the channel at the opposite side of the post. The slot 25 is shown in Fig. 2, as having 55

a dip 29, at one end for locking the arm against straight horizontal withdrawal over the two pins and requiring the table to be slightly lifted before it can be slid outwardly or to the right in Fig. 2, for clearing the end slot 27, from pin 28, to permit the arm to hinge downward at the side of the post, Fig. 6. The bottom of the channel beneath the pivot pin 26 is indicated in these views as cut away to permit the supporting arm 12, to swing directly downward at the side of the post.

The rotary or angular adjustment of the table top is accomplished by providing the top with a center tube 30, projecting at one end as in Fig. 2, to enter a cylindrical socket 31, in the end of the arm 12. This socket is split at the bottom at 31a, to form a split clamp which can be closed to frictionally grip the center tube or rod 30, by a clamp nut 32.

The table top is shown as constructed of light sheet metal having backwardly flanged ends 33, 34, the first or inner one secured by a sleeved portion 35, over the tube 30, and the second or outer flange secured to the end of the tube at 36. The side edges, which in the use of the table as a book support, would be at the top and bottom as indicated in broken lines, Fig. 1, are shown as flanged forwardly at 37, to support books or reading matter, or the like.

Page holders are shown in the form of wires 38, overstanding the face of the table and having angled end portions 39, terminating in inwardly directed points 40, entered in seats 41, in the end flanges 33, 34. When not in use, these book holding wires may be hinged outwardly or toward the edges of the table top, so as to lie close to the edge flanges 37. When required, they may be turned up to overlie the book pages, paper, or the like, and if desired, they may be entirely removed by springing the inwardly turned ends 40, out of the flange openings 41. By provision of a series of openings 41, at different points along the end flanges, these page holding elements may be shifted to suit requirements or a greater number than two of them be employed.

To prevent accidental tipping of the top when employed as a horizontal table for supporting dishes or the like, a suitable catch or locking device may be employed, such as the spring pressed bolt indicated at 42, Figs. 1, 5 and 6, adapted to enter an appropriately placed seat 43, in the inner end flange 33. If desired, other notches or seats may be provided for enabling this bolt to lock the table top in various other relations.

When folded as in Figs. 6 and 7, the table occupies relatively small space. Catches or other devices may be provided for retaining the parts in folded relation. In the illustration, a spring latch is indicated on the table tube at 44, Fig. 6, to snap into engagement with a retainer 45, on the base. With the clamp screws 23 and 32 tightened, the parts will be retained in this closed or folded relation. Unfolded or set-up as in Fig. 1, the table may be adjusted for height and for inclination of the top relative to the horizontal. The table is light enough to be readily shifted into different positions on a floor. In addition to being adjustable in various ways, the structure is readily separable. Upon loosening clamp screw 32, the table top may be withdrawn from the split supporting clamp 31. The loosening of clamp screw 23, permits the post 11, to be lifted out and separated from the supporting column 10. While this column is shown as a cylindrical tube carry-

ing a square socket for the post, it is contemplated that said column may be in the form of square tubing of a size to receive the sliding post 11. Various other changes may be made, but the parts constructed as shown are particularly light and at the same time, strong enough to carry the loads to which a table of this character would be subjected. The pivoting of the feet to the two sides of the generally triangular base locates the feet so that they will have the desired divergent outstanding relation in the downward supporting position and so that in the upper folded relation, the angular extensions at the ends of the feet will form supporting continuations of the bottom face of the base. The third side of the triangular base as indicated in Fig. 6, serves as a stop for the table top to fold against. By locating the pins 26 and 28 in the channelled portion of the supporting head at opposite sides of the post, a wide mounting for the table carrying arm is provided and this arm is enabled to swing down freely at the side of the supporting column.

When the table is used for supporting a relatively heavy object, such as a typewriter for instance, the outer end of the table may be independently supported as by an auxiliary leg or standard collapsible in the tubular supporting member 30. This feature is particularly shown in Figs. 1, 2, 9 and 10, where legs 50 are illustrated in the form of stiff struts slideable into the tube 30, and loosely pivoted at 51, to the outer end of a plug 52, also slideable in tube 30. When these auxiliary legs or struts are drawn out from the concealed position, Figs. 1 and 2, and dropped down at the end of the table as in Figs. 9 and 10, they may be braced in the spread apart supporting relation as by a hinged connecting bar 53, Fig. 10.

What is claimed is:

1. An adjustable folding table, comprising a column having a generally triangular base, divergent feet pivotally mounted on two of the sides of said generally triangular base, foldable about the pivotal centers upward alongside the column and provided with angular end extensions beyond the pivotal centers projecting beyond the base when the feet are extended in divergent relation and arranged to form substantial continuation of the bottom of the base when the feet are pivoted upward into substantially parallel relation at the sides of the column and a table top vertically adjustable on the column and hinged to fold downward over the third side of the generally triangular base and to be lowered into line with the bottom of the base.

2. A table of the character disclosed, comprising a supporting column having a generally triangular base, divergent supporting feet pivoted at two of the sides of said generally triangular base in position to be rotated about the pivotal centers downwardly and then upwardly into substantially vertical position alongside the column and a stop member extending across the third side of the base and engageable over the divergent feet to prevent upward collapsing movement of said feet, said feet having relatively divergent portions projecting beyond the pivotal connections with the base angularly in respect to said feet and engageable with a supporting surface to oppose folding movement of the column away from said feet and to brace the column against tipping along the lines of said divergent feet.

3. An adjustable folding table, comprising a substantially triangular base, an upstanding tubular column on said base, supporting feet pivoted

to two of the sides of said substantially triangular base, stop shoulders at the third side of the substantially triangular base overstanding said feet in the projecting relation of the latter and said feet adapted to be rotated on the pivotal supports for the same from beneath said overstanding shoulders downwardly and then upwardly into position at opposite sides of the upstanding column, a vertically adjustable post held non-rotatably in said column and a table top pivoted

substantially horizontally to said post and at the side of said post over said third side of the substantially triangular base and whereby said table top may be swung downward on said substantially horizontal pivot over said third side of the substantially triangular base, adjoining said upwardly rotated feet at the sides of the column and be lowered to the level of the base. 5
